UNITED STATES PATENT OFFICE.

EVERETT L. LAKE, OF SYRACUSE, NEW YORK.

BREECH-LOADING FIRE-ARM.

SPECIFICATION forming part of Letters Patent No. 310,689, dated January 13, 1885.

Application filed September 1, 1884. (No model.)

To all whom it may concern:

Be it known that I, EVERETT L. LAKE, a citizen of the United States, residing at the city of Syracuse, in the county of Onondaga and 5 the State of New York, have invented a new and useful Improvement in Breech-Loading Fire-Arms, of which the following is a specification.

My invention relates to improvements in 10 the mechanism for breech-loading fire-arms, whereby the hammer and lock are dispensed with and throwing out the broken shells and inserting new cartridges are simplified.

Figure 1 is a sectional view of the gun assembled, wherein my invention largely appears. Fig. 2 shows the stock when swung open to eject the shells and receive new cartridges. Fig. 3 shows the ratchet and star-wheels, hangers, and forked vibrating spring, 20 &c.

Similar letters refer to similar parts in the several views.

A represents the breech or stock of the gun, in which the plungers P, the vibrating spring 25 S, the trigger-plate with the jointed lever or trigger L, with the springs s and s", the ratchet R, star-wheels R' R", shaft c, spring t, and dovetailed groove g are located and supported.

B represents the barrels; C, the axle upon 30 which the barrels revolve, with the furrow 1 and cam-groove 2 and flat surfaces i and m; k, the key; l, the ejector-lever; s', a spring; E, the extractor; b, the locking-bolt, with slot and spiral spring; w, the arms, with shoulders a extending back from the butt-end of 35 the barrels into the dovetailed groove g of the stock, and G the guard to protect the forked vibrating spring. The spring S is fastened to the stock back of the trigger, and is bent 40 to form a guard therefor. Near where it passes through the trigger-plate it is split, and on entering the stock it is forked or V-shaped, and the respective ends enter the notches n in the right and left plungers. The front edge 45 of the slot o in the trigger-plate, through which the spring passes in entering the stock, acts as a stop for the spring, while the inside of the stock is so cut away that the ends of the spring whip forward and carry the plungers 50 forward to explode the cartridges, and then

vibrate to such a position of rest that the plungers are entirely within the breech or stock.

c is a shaft supported by hangers, upon which are placed the ratchet-wheel R and the star-wheels R' R", (see Fig. 3,) arranged so that the ratchet-wheel R connects with the lever or trigger L, and the star-wheel R' with the right and the star-wheel R" with the left hand plunger. There are two notches on the 55 ratchet-wheel R to one on the star-wheels R' or R", and these star-wheels are so fastened to the shaft c that the notches on the respective wheels are in line with the alternate notches on the ratchet-wheel, so that when 60 the point on the star-wheel R' enters the notch r of the right-hand plunger and the plunger is drawn back by pressure upon the power end of the trigger the other end engages the ratchet-wheel R until the star-wheel R" passes 65 the point of connection with the plunger, and the plunger is left free to explode the cartridge, and the trigger is restored to its position of rest by the spiral spring s". Then the point on the star-wheel R" enters the notch r 70 of the left-hand plunger, and in like manner is drawn back and let go, and thus alternately 75 the barrels are discharged. By pressing upon the head of the shaft c the coil-spring t is 80 pressed back and the star-wheels R' R" are thrown out of connection with the plungers, and then the trigger may be drawn back without drawing back or discharging either plunger. By this arrangement the same barrel may be repeatedly discharged. The end 85 of the locking-bolt b is so beveled that when the stock of the gun is in the right hand, and the left hand, being upon the barrels, is twisted around, the bolt is pressed back and the barrels revolve upon the axle C. The screw 90 in the slot in the bolt b keeps it from being thrown out of place by the spring. The arms w, with the shoulders a, pass through the grooves g in the line of a circle. The key k, extending through the lug of the barrels and 95 across the axle C in the furrow 1, keeps the barrels in place while revolving about the axle C. The foot of the ejector-lever l rests in the cam-groove 2 of the axle C, while the top of the ejector-lever enters a mortise in the extractor, 100

and when, by the revolution of the barrels, the foot of the ejector-lever reaches the incline and passes thereover the broken shells are thrown out, and after passing the highest point of the incline the extractor is drawn back to its position of rest quickly by the power of the spring s' , the groove being cut out to allow a backward movement of the foot of the ejector. When the key k and the foot of the lever l reach the flat places i and m , respectively, on the axle C , the barrels can be removed from the stock. By jointing the trigger so that when at rest it forms an angle about one-fourth less than a right angle, and when pulled back to discharge the gun it is straight, (see Fig. 1,) I greatly reduce the power necessary to be applied to the trigger to operate the discharging mechanism of this class of guns, and very nearly approach the feather-touch requisite to true aim in discharging a gun. The dovetailed groove g receives the shoulders a of the arms w , and securely locks the barrels to the breech or stock.

It is obvious that I have greatly reduced the number of pieces ordinarily in use in breech-loading hammerless guns; also, that I might use two springs instead of the V-shaped spring S ; but I prefer the latter, because simpler and equally effective.

I am aware of the several devices in use in this class of guns, and especially of my previous Patent No. 284,213, and hence

What I claim is—

1. The jointed trigger L , having springs s

s'' , in combination with the ratchet-wheel R , 35 star-wheels $R' R''$, and notched plungers $P P$, said ratchet-wheel and star-wheels being mounted on a longitudinally-movable shaft, e , substantially as described.

2. The right and left plungers $P P$, provided 40 with notches r , which engage the star-wheels $R' R''$, and having mortises n , which receive the free ends of the spring S , in combination with the spring S , star-wheels $R' R''$, ratchet-wheel R , sliding shaft e , having spring t , and 45 the jointed single trigger L , to alternately discharge both barrels of a gun or successively discharge either barrel, substantially as described.

3. The spring S , attached at one end to the 50 outer side of the gun-stock, and bent to form the trigger-guard, the inner end of said spring being bifurcated and inclosed in the gun-stock, in combination with the plungers $P P$, having 55 mortises n and notches r , the ratchet-wheel R , and star-wheels $R' R''$, mounted on a shaft, e , and the jointed trigger L , having springs $s s''$, substantially as described.

4. The forked spring S , bent to form the 60 trigger-guard, in combination with the plungers $P P$, and a trigger-plate having a guard, G , and a slot, o , the front edge of said slot being adapted to serve as a stop for the spring, substantially as described.

EVERETT L. LAKE.
